(57) **CLAIM**

(21) Appl. No.: **29/563,912**

The ornamental design for a hook assembly for a tackle box insert, as shown.

(22) Filed: **May 9, 2016**

DESCRIPTION

(51) **LOC (10) Cl.** **03-01**

FIG. 1 is an isometric view of a hook assembly for a tackle box insert showing my new design;

(52) **U.S. Cl.**

FIG. 2 is an enlarged side elevational view thereof;

USPC **D3/318**

FIG. 3 is a right side view thereof;

(58) **Field of Classification Search**

FIG. 4 is a back view thereof;

USPC D3/260, 318; D8/372

FIG. 5 is a front view thereof;

CPC A01K 97/06

FIG. 6 is a top view thereof; and,

See application file for complete search history.

FIG. 7 is a bottom view thereof.
